Primary Examiner — Sheryl Lane*Assistant Examiner* — Ieisha N Price(74) *Attorney, Agent, or Firm* — Bauer and Joseph(57) **CLAIM**

The ornamental design for a mesh fastener, as shown and described.

DESCRIPTION

FIG. 1 is a top perspective view showing my new design; FIG. 2 is a bottom perspective view thereof;

FIG. 3 is a top view thereof;

FIG. 4 is a right side view thereof;

FIG. 5 is a left side view thereof;

FIG. 6 is a front view thereof;

FIG. 7 is a rear view thereof; and,

FIG. 8 is a bottom view thereof.

The mesh fastener is shown with a symbolic break in its length. The appearance of any portion of the article between the break lines forms no part of the claimed design.
